UNITED STATES PATENT OFFICE.

HENRI GEORGE, OF PARIS, FRANCE, ASSIGNEE, BY MESNE ASSIGNMENTS, TO HANOVIA
CHEMICAL & MANUFACTURING COMPANY, OF NEWARK, NEW JERSEY, A CORPORA-
TION OF NEW JERSEY.

PROCESS FOR INCREASING THE EMISSION IN THE ULTRA-VIOLET REGION FROM MERCURY-VAPOR LAMPS.

Application filed May 26, 1925, Serial No. 32,959, and in France May 30, 1924.

The present invention relates to a process and apparatus for increasing the emission in the ultra-violet region from mercury vapor lamps.

5 It is known that mercury vapor lamps with quartz envelopes constitute a source of ultra-violet rays giving an excellent efficiency. It is likewise known that such lamps can be supplied directly with alternating current, by keeping within the conditions defined in the French Patent No. 493,026, dated 24th April, 1918. A comparison of the spectra emitted in analogous conditions by mercury vapor lamps supplied 10 respectively with continuous current and with alternating current, shows that by varying the voltage and frequency in the latter case the distribution of the energy in the spectrum is varied to a great extent. The 15 applicant has ascertained that the higher the voltage and the frequency of the current supplied, the greater will be the radiation in the ultra-violet region. Thus, for equal amounts of energy expended, a ten-fold increase of certain ultra-violet rays can be obtained when the lamp is supplied with alternating current at high voltage and high frequency.

This method of supply, which forms the 20 subject of the present invention, has thus for effect to increase the efficiency or yield of the mercury vapor lamp as regards ultra-violet radiations.

The invention also comprises an apparatus for carrying out this process; the apparatus is characterized by an arrangement and combination of parts for transforming the alternating current of the local supply into a high frequency current, connected between the current-supply terminals and the mercury-vapor lamp with quartz wall or envelope.

The accompanying drawing represents diagrammatically by way of example a form 45 of construction of this apparatus.

The mercury vapor lamp consists of a tube 1 in the shape of an inverted U made of transparent silica, connecting two vessels 2, 2; the latter contain mercury and are fitted with the electrodes 3, fixed in any suitable manner, as by grinding, sealing, etc. Along the tube 1 there is attached or fused on a vessel 4, the dimensions of which are

calculated so as to ensure stable operation of the lamp. The tube is preferably filled 55 with an inert gas, such as argon or neon, at a pressure of some centimetres of mercury; the pressure of this gas has for its object to ensure the lighting or starting of the lamp and its operation on alternating current. If 60 preferred, without departing from the principle of the invention, the mercury vapor may be utilized alone as gas, the tension of this vapor being raised by any suitable means, such as the heating of the vessel 2, 65 to a value adapted to ensure the lighting and operation of the lamp.

Between the current supply terminals 5, 5 of the local system, and the electrodes 3, 3, there is interposed the device for transforming the local alternating current into a high frequency current; this device may consist of the conventional arrangement comprising a transformer 6, inductance 7, capacities 8, 8, and spark-gap 9; the mercury vapor lamp 75 is connected, as shown to the terminals of the inductance 7. It is obvious that any other arrangement may be used in which the lamp is connected to the terminals of the inductance of an oscillating circuit. 80

Apart from the technical advantage of the increased yield, the process described presents other advantages of a practical nature in the commonest applications of mercury vapor lamps, namely to scientific and therapeutic uses. Since high frequency currents are comparatively harmless, the process described allows of much readier manipulation of the apparatus without fear of accidents. Another practical advantage results from 90 the fact that the device employed for transforming the local alternating current into high frequency current may be utilized for other purposes, in the laboratory, for example, for the production of sparks for spectroscopy, and by medical practitioners, for example, for high-frequency treatment, especially diathermy; this allows of considerable saving in the total cost of equipment. 95

What I claim is:

1. In combination with a mercury vapor lamp having a quartz envelope, means for increasing the ultra-violet emission of the lamp comprising a source of high frequency, high voltage current, and means for connecting the terminals of the lamp to the terminals 105

nals of said source of current so that the mercury vapor in the lamp will serve as a conductor of the high frequency, high voltage current.

5. 2. In combination with a mercury vapor lamp having a quartz envelope, means for increasing the ultra-violet emission of the lamp comprising a source of current, means interposed between the lamp and the source
- 10 of current for converting the supply current into high frequency high voltage current, the terminals of the lamp being so connected to the interposed means that the mercury vapor in the lamp will serve as a conductor
- 15 for the high frequency high voltage current.

3. An apparatus for increasing ultra vio-

let ray emission of a mercury vapor lamp with quartz envelope comprising a source of current, a high frequency high voltage oscillating circuit interposed between the lamp 20 and the source of current, said circuit comprising the secondary of a transformer in parallel with an inductance, a spark gap, and condensers in series with the inductance, the terminals of the inductance being connected to the terminals of the mercury vapor lamp so that the mercury vapor in the lamp 25 will serve as a conductor of the high frequency high voltage current.

In testimony whereof I have signed my name to this specification.

HENRI GEORGE.
